Patented Sept. 20, 1921.

By *William Leontow*
Attorney

UNITED STATES PATENT OFFICE.

FRANS MARINUS MEYER, OF AMSTERDAM, NETHERLANDS.

WATER-TUBE BOILER.

1,391,558.

Specification of Letters Patent. Patented Sept. 20, 1921,

Application filed April 19, 1919. Serial No. 291,279.

To all whom it may concern:

Be it known that I, FRANS MARINUS MEYER, residing in Amsterdam, 1ste Helmerstraat No. 238, subject of Netherlands, have invented certain new and useful Improvements in Water-Tube Boilers, of which the following is a specification.

This invention relates to water tube boilers, and the object thereof is to improve the construction of water-tube-steam boilers and particularly to provide a simple and cheap construction and at the same time to provide means for preventing leakage at the different joints between the tubes, headers or boxes and steam drum.

With this object in view the invention consists in a water-tube boiler, wherein the front and back-headers are connected by means of bent or curved water-tubes welded to said headers, said headers being attached to the steam-drum by means of movable and adjustable connections in such a manner that the headers and water-tubes are able to expand freely and independently of the steam-drum.

The invention further consists in a water-tube boiler wherein the front-headers are separately movable and adjustable relatively to the steam-drum, while the back-headers are collectively movable and adjustable relatively to the drum.

A T-shaped steam and water-drum is employed in conjunction with a number of front and back-headers or boxes, the front and back-headers being connected to each other by a bank of bent or curved water-tubes, which are welded to the headers. Each front header is connected to the transverse portion of the drum by means of a hollow fitting with adjustable and movable conical or ball connections, the back-headers being coupled by means of common flanges to a horizontal collecting tube or mud-drum, the latter being at each end connected to the steam-drum by means of a vertical tube having two adjustable and movable conical or ball connections.

Contrary to the existing types of water tube boilers, boilers constructed according to the present invention may be constructed very cheaply, on account of the simple and durable connection of the water-tubes and headers. Again the inconvenience of leakage will be reduced to a maximum, since welded connections are less likely to leak than screwed or rolled ones, and moreover,

the water-tubes and headers, mud-drum and its tubes are movable with relation to the steam-drum as well as to each other, on account of the fact that their connections are adjustable and movable.

This feature, in connection with the curved form of the water-tubes, allows a free and independent expansion of the various parts and avoids dangerous stresses in the parts of the apparatus and also leakages and other inconveniences.

The boiler may be easily taken to pieces and assembled afterward very rapidly, but little skilled assistance being required.

A constructional form of a boiler according to the invention is shown in the accompanying drawings.

Figure 1 is a side view of a welded water-tube boiler;

Fig. 2 is a sectional view taken on the line 2—2 of Fig. 1.

Fig. 3 is a top view of a welded water-tube boiler;

Fig. 4 is a front view of a welded water-tube boiler;

Fig. 5 is a partial sectional elevation of a connection between the steam header and each water-tube element separately;

Fig. 6 is a detail section of a movable connection between the steam drum and the movable connection of the water-tube elements.

Fig. 7 is a side view of a water-tube element.

The improved water-tube boiler comprises a T-shaped steam-drum 1, riveted in the usual way and which may be fitted with a steam-dome 2 and 3 is a cross-tube riveted to the rear part of the steam-drum. 4 are vertical tubes which are connected at 5 to the cross-tube 3, and at 6 to the horizontal connecting tube or mud-drum 11. In order to make said connections movable, adjustable and steam-tight, the ends of the tubes 4 are suitably formed with a conical or spherical surface 8, adapted to be seated in a steam-tight manner in the conical or spherical seats 7 of the cross-tube 3 or the mud-drum 11, as shown in Fig. 6. Both tubes 4 are fitted adjacent their ends with flanges 4' against which bear rings 10. Suitable bolts 10', connect the flanges 9 and rings 10 and maintain the surfaces 7 and 8 in steam-tight contact and permit of adjustment of the joint. The back-headers 14, are attached to the mud-drum 11 by any

known means such as flanges and bolts. The front-headers 15 communicate by means of hollow nipples 16 with the steam-drum 3', and the water-tubes 13 are welded to the 5 headers 15 and are bent or curved to permit expansion.

The front-headers 15 are connected to the transverse portion of the T-shaped steam-drum 3' by means of the fittings shown in 10 Fig. 5. These fittings each consists of a hollow nipple 16, having a conical upper portion adapted to fit in a conical opening of the steam-drum, and a curved lower portion adapted to fit in a correspondingly 15 curved seat formed in the end of the headers 15. The upper and lower parts of the nipples 16 are caused to make steam-tight contact with their seats by means of the bolt 17. The bolt 17 is secured at the lower 20 end to the header 15 and passes at its upper end through an eye in a brace 18. A nut 19 on the end of the bolt 17 and bearing on the brace 18, maintains the nipple 16 in steam-tight engagement with its seats, and 25 permits adjustment of the joint.

The steam-drum 1 is suspended toward

the rear by a strap 20, in order to allow said drum to expand freely.

Having now particularly described and ascertained the nature of my said invention 30 and in what manner the same is to be performed, I declare that what I claim is:

In a watertube-boiler consisting of a steam drum, front and backheaders and muddrum, and the headers connected to each 35 other by means of bent watertubes welded to said headers, said steamdrum being of T-configuration, the front headers being separately and movably connected to the cross-leg of the T-shaped steamdrum, the 40 said backheaders being each connected to the muddrum, the latter being movably connected to the other leg of said T-shaped steamdrum.

In testimony that I claim the foregoing 45 as my invention I have signed my name in presence of two subscribing witnesses.

FRANS MARINUS MEYER.
